UNITED STATES PATENT OFFICE.

GEORGE WASHINGTON NEWMAN, OF CHICAGO, ILLINOIS, ASSIGNOR TO WILSON-JONES
LOOSE LEAF CO., OF CHICAGO, ILLINOIS, A CORPORATION OF MASSACHUSETTS.

LOOSE-LEAF DEVICE AND METHOD OF ASSEMBLY.

Application filed September 20, 1924. Serial No. 738,743.

To all whom it may concern:

Be it known that I, GEORGE WASHINGTON NEWMAN, a citizen of the United States, and a resident of the city of Chicago, in the county of Cook and State of Illinois, have invented certain new and useful Improvements in a Loose-Leaf Device and Method of Assembly; and I hereby declare that the following is a full, clear, and 10 exact description of the same, reference being had to the accompanying drawings, and to the numerals of reference marked thereon, which form a part of this specification.

This invention relates to a loose leaf device and the method of making the same and concerns itself primarily with the means and manner of securing the rings to their supports.

In the past it has been customary in the 20 construction of such devices to provide suitable slots in the toggle plates or base plates that sustain the rings, and provide tongues upon the rings for extending through the slots in such plates. These tongues would 25 then be swaged over. In practice it has been found that ring hooks secured in such a manner would soon work loose. The metal ring plates are usually thin especially in small ring hooks so that the walls of the 30 slots have little resistive power.

It is an object of this invention to overcome this defect by anchoring hooks upon their base plates so that the same will be firmly retained and not liable to work loose.

With this and other objects in view which will become more apparent in the following description and disclosures this invention comprises the novel structure and combinations hereinafter described and more particularly pointed out and defined in the appended claims.

In the accompanying drawings, which illustrate a preferred embodiment of this invention and in which similar reference numerals refer to similar features in the different views:

Figure 1 is a plan view of a loose leaf holding device involving this invention.

Figure 2 is an enlarged side elevational 50 view of one of the ring hooks.

Figure 3 is an enlarged front elevational view of one of the ring hooks.

Figure 4 is an enlarged perspective and fragmentary view of one of the ring holding plates.

Figure 5 is an enlarged elevational view of a ring hook inserted in a slot in the base plate.

Figure 6 is a view similar to Figure 5 showing the ring hook secured in the base plate.

Figure 7 is a part sectional and part elevation view upon an enlarged scale of the secured ring hook.

Figure 8 is a plan view of a ring hook holding plate.

Figure 9 is an enlarged sectional view upon the line 9—9 of Figure 1.

As shown on the drawings:

The form of loose leaf holding device that is illustrated in connection with my invention consists of a pair of toggle plates 1 sustained by a resilient bowed plate 2. Double headed rivets 3 connect the adjacent edges of the toggle plates. The invention concerns itself with the structure and method of securing the ring hooks which are designated by the reference 4 to the toggle plates, which are rather thin and hence cannot afford a very solid foundation.

According to this invention, the base plates 1 for the ring hooks are provided with slots 5 which are preferably stamped therein in such a manner as to provide a depending lip 6 at one end of each slot which inclines forwardly. The ring hooks are provided at their base with a tongue 7 which is adapted to fit in such slots. This tongue is usually stamped or formed by flattening the outer portion of the base of the ring. This stamping operation produces a tongue which is slightly rounded at its front end or toe as indicated at 8, and which slopes at its heel 9 where it merges into the ring proper. One of the difficulties heretofore encountered existed in the fact that there was nothing to sustain the heel of the hook when assembled and nothing except the lateral swaged flanges to sustain the toe. Consequently the ring hooks would soon work loose. According to this invention, the tongues of the ring hooks are firmly anchored at the heel and toe, as well as upon the sides so that there is very little tendency for the hooks to work loose.

In assembling, the ring hooks upon a base plate, the tongues of the hooks are inserted in the slots, the tongues and forwardly inclined lips 6 are then simultaneously swaged

over the back of the plate; the force applied to the inclined lips has a considerable forward component which causes them to bite in the heels 9 of the tongues and flatten the same to provide an efficient heel support as shown in Figure 6. At the same time, the tongues are jammed against the forward end of the slots thereby flattening the toes to some extent. This forward pressure together with the swaging operation causes the metal of the tongues to overflow or overlap the forward ends of the slots as shown at 10 in Figure 6 for resisting the rearward pressure on the ring hooks when in use.

From the foregoing, it will be apparent that the tongues 7 are firmly secured and braced both at the heels and toes to resist the pressure applied thereto which is normally in the plane of the ring hooks. The laterally swaged flanges will readily resist any lateral strains.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

30 1. In a loose leaf device, a base plate, having a slot with a depending lip, a ring hook having a tongue extending into said slot, said tongue being swaged over said plate and said lip being swaged into said tongue.

35 2. In a loose leaf device, a base plate having a slot with a depending lip, a ring hook having a tongue extending into said slot and having a toe and heel; said lip being swaged against the heel of said tongue; the tongue being swaged over said plate overlapping said toe.

40 3. In a loose leaf device, a base plate, a ring hook having a tongue with a toe and heel anchored in said plate, said base plate having bracing means for the heel and said tongue overlapping said base plate at the toe.

45 4. In a loose leaf device, a base plate, a ring hook having a tongue with a heel an-

chored in said base plate, said plate having means lapped against said heel and said tongue being swaged over the back of said plate.

5. The method of attaching a ring hook to a base plate consisting of forming a slot 55 in said plate with a depending lip, inserting said ring hook in said slot and simultaneously swaging the end of said ring hook over said plate and said lip against the heel of said hook.

6. The method of attaching ring hooks to a base plate consisting of forming slots in said plate with depending lips, inserting said ring hooks in said slots, and simultaneously swaging the ends of said hooks over 65 said plate and said lips against the heels of said hooks.

7. The method of attaching a ring hook to a base plate which consists in forming a slot in said plate with a depending lip, inserting the end of said hook in said slot, crimping the end of said hook over said plate and pressing said lip to bite into the heel of said hook.

8. In a loose leaf device a base plate having a slot and a depending lip, a ring hook having a tongue adapted for fitting said slot, said tongue having upper shoulders resting on said base plate, and said tongue being swaged over the sides and front of said slot 80 and said lip being swaged to bite into the heel of said tongue.

9. In a loose leaf device, a base plate having a slot formed to provide embracing means at one end, a ring hook provided with 85 a tongue having a heel and toe fitting said slot, said tongue terminating in upper shoulders and being swaged over the sides and front of said slot and said embracing means being swaged against said heel.

In testimony whereof I have hereunto subscribed my name in the presence of two subscribing witnesses.

GEORGE WASHINGTON NEWMAN.
